UNITED STATES PATENT OFFICE.

LEW ARNTZ, OF DES MOINES, IOWA.

FASTENER FOR ENVELOPES.

1,417,790.

Specification of Letters Patent. Patented May 30, 1922.

Application filed March 14, 1921. Serial No. 452,204.

To all whom it may concern:

Be it known that I, LEW ARNTZ, a citizen of the United States, and a resident of Des Moines, in the county of Polk and State of Iowa, have invented a certain new and useful Fastener for Envelopes, of which the following is a specification.

The object of my invention is to provide an envelope fastener, whereby it will be difficult to open the envelope without the mutilation thereof, the parts being of simple, durable, and inexpensive construction.

More particularly, my invention relates to a fastener device for envelopes which is so adapted that when once closed, the envelope closure flap cannot be opened for gaining access to the contents of the envelope without the mutilation of the envelope.

It will be understood that with the ordinary glue type of envelopes the envelope may be steamed and opened, and then sealed again without the addressee knowing of it.

My invention is provided to overcome this serious problem. My invention is also adapted to be used as a closure device for cartons, boxes, and the like.

With these and other objects in view my invention consists in the construction, arrangement and combination of the various parts of my device, whereby the objects contemplated are attained, as hereinafter more fully set forth, pointed out in my claim, and illustrated in the accompanying drawings, in which:

Figure 1 is a view of an envelope with my improved fastener device shown thereon.

Figure 2 is an enlarged exaggerated sectional view taken on line 2—2 of Figure 1.

Figure 3 is an enlarged plan view of the plate forming part of my device.

Figure 4 is a view of one of the plates and pin member which are secured to the body portion of the envelope or the like, and

Figure 5 is a perspective view of a container with my improved fastening means shown thereon.

In the accompanying drawings I have used the reference numeral 10 to indicate an ordinary envelope which is provided with a closure flap 11. The closure flap 11 is of the ordinary type and provided with the ordinary glue for sealing of the envelope.

My improved device which is designed to prevent any tampering with the envelope comprises a plate 12 and fingers 13 extending radially from its periphery, the fingers 13

extending through the body portion of the envelope 10 and are clinched for securely holding the plate 12 to the body of the envelope.

The plate 12 is provided with a central opening which has its edge curved as at 14, so as to form a slight flange. The body portion of the envelope 10 is provided with an opening which registers with the opening in plate 12. Extending through the opening in the plate 12 and resting against the flange 14, is a pin member 15, made of comparatively soft material.

The pin member 15 is provided with a head 16, which prevents it from passing through the opening in plate 12. In this connection, it will be understood that the pin member 15 and plate 12 may be formed integral. The upper outer end of the pin member 16 is slightly contracted as at 17. The purpose of which will be hereafter more fully set forth.

Secured to the closure flap 11 is a plate 18 and fingers 19 extending radially outwardly from its periphery. The fingers 19 are projected through openings in the closure flap 11 and are clinched so as to securely hold the plate 18 to the closure flap 11. The plate 18 is provided with a central opening 20 which registers with an opening in the closure flap 11 and with the pin member 15.

The material around the opening 20 in the plate 18 is slit as at 21. The slitting of the material of plate 18 around the opening 20 as shown in Figure 3 of the drawings causes movable finger members 22 to be formed.

It will be understood that the plate 18 is formed of resilient material so as to permit the movable fingers of 22 to be sprung to various positions.

In the practical operation of my device the closing of the closure flap will cause the pin member 15 to be projected through the opening 20 in the plate 18.

The diameter of the opening 20 is slightly less than the diameter of the pin member 15. When the pin member 15 is forced into the opening 20 it will cause the movable fingers 22 to be sprung outwardly, as shown in Figures 2 and 3 of the drawings.

The inner edge of the fingers 22 grip and engage the pin member 15. The contracted portion 17 of the pin member 15 permits the easy starting of the plate 18 on to the pin member 15. When the plate member 18 has been moved its full limit of movement,

the envelope is then securely fastened. If the envelope were to be opened any outward movement of the flap would cause the movable fingers 22 to more firmly engage the pin member 15.

From the construction of the parts just described it will be seen that if the envelope is to be opened the envelope must be mutilated. In the Figure 5 of the drawings I have 10 shown my fastener device as applied to a box or container.

A box 23 is provided which has a closure flap 24 thereon. A series of fastener devices are provided on the body of the box 23 and 15 the flap 24, which when they coact will cause the flap 24 to be securely locked.

It will be understood that my fastener is applicable to a great many containers and the like. By providing the plates 12 and 20 18 of substantial sizes it prevents their accidental removal from the envelope 10 and closure flap 11 which are of paper or other fragile material.

It will be seen that my device will substantially eliminate the unauthorized opening of 25 envelopes and sealing them again by what may be termed the "steam process."

Some changes may be made in the construction and arrangement of the parts of 30 my machine without departing from the real spirit and purpose of my invention, and

it is my intention to cover by my claim, any modified forms of structure or use of mechanical equivalents, which may be reasonably included within its scope.

35

I claim as my invention:

In combination with an envelope or container having a closure flap thereon, a fastener device for preventing the opening of the envelope or container without the mutilation thereof, said device including a plate secured to the back of the envelope or container, said plate having an opening formed therein, an outwardly extending curved flange formed on the edge of said opening, a pin received in said opening having a head thereon, the head on said pin being received on the under side of said plate and resting against the curved flange, a second plate secured to the closure flap of the envelope or 40 container, said second plate being provided with an opening adapted to receive said pin member when the closure flap is in closed position, means for preventing the opening of said closure flap when once closed, 45 said means comprising resilient fingers formed on said second plate, said fingers being designed to coact with the pin member for preventing movement in one direction as specified.

Des Moines, Iowa, March 10, 1921.

LEW ARNTZ.
